UNITED STATES PATENT OFFICE

FREDERICK W. BISHOP, OF WEST HAVEN, CONNECTICUT.

IMPROVEMENT IN ADJUSTABLE CARRIAGE OR SLEIGH POLES.

Specification forming part of Letters Patent No. 178,899, dated June 20, 1876; application filed March 13, 1876.

To all whom it may concern:

Be it known that I, FREDERICK W. BISHOP, of West Haven, in the county of New Haven and State of Connecticut, have invented certain new and useful Improvements in Carriage-Poles; and I do hereby declare that the following is a full, clear, and exact description of the same, reference being had to the accompanying drawings, forming a part of this specification, in which—

Figure 1 represents a top view of my improved carriage-pole, and Fig. 2 a bottom view of the connecting-pole socket.

This invention has relation to that class of carriage-poles that are capable of being adjusted and readily fitted to any width of vehicle or sleigh.

The object and purpose of the present invention are to materially decrease the weight of the adjustable pole, and so construct the several parts thereof that they will be light, durable, and effective in their operation.

My invention therefore consists of a T-shaped socket formed of a single piece of metal, and with downwardly-projecting flanges, by which the same may be readily secured to the end of the carriage-pole, and also for the reception of the inner ends of the curved bars, said bars being secured to pivoted or swinging braces, and adjusted and held within the T-shape socket by a bolt and nut passing through the same and through elongated slots within the socket.

In the drawings, A represents the carriage-pole, and B the stays or braces, which are pivoted at a to the plates a' , said plates being bolted or otherwise secured to the pole A. The curved bars C are preferably of wood, to reduce as much as possible the weight of the several parts, and are secured to the stays or braces B by suitable rivets or bolts.

The T-shaped socket D, which I deem the essential part of my invention, is formed of a single piece of metal by swaging or stamp-

ing, or may be cast, if desired, and has downwardly-projecting flanges b b' , as illustrated in Fig. 2. This form of socket is capable of being readily connected to the end of the pole A by placing it within the socket formed by the flanges b b' , and securely riveting it thereto. The other portion of the socket formed by the flanges b b' receive the inner and free ends of the curved bars C, and are capable of being adjusted therein to bring their outer ends toward or from each other by screw bolt and nuts c passing through the ends of the same and through elongated slots d in the socket. The pole thereby being readily adjusted and attached to any vehicle by first loosening the clamp-nuts of the bars and setting the stays into the position required, after which the bolts and nuts are tightened, thus establishing the rigid connection of the bars to the pole in a strong, durable, and substantial manner.

It will be seen that the T-shape socket is capable of being manufactured at a very trifling cost, which not only greatly lessens the expense in the manufacture of this class of devices, but makes a much lighter and nicer finished connection between the pole and adjustable bars C, and also materially strengthens the pole at its point of greatest strain and liability to fracture.

Having described my invention, what I claim as new, and desire to secure by Letters Patent, is—

The T-shaped socket D, formed with flanges b b' and elongated slots d , in combination with the pole A, pivoted stays or braces B, and the arms C, the latter being adjustable within the socket D by bolts and nuts c , substantially as and for the purpose specified.

FREDERICK W. BISHOP.
